UNITED STATES PATENT OFFICE.

HARRY L. TANNER, OF BROOKLYN, NEW YORK, ASSIGNOR TO THE TANNER ENGINEERING COMPANY, INC., OF BROOKLYN, NEW YORK, A CORPORATION OF NEW YORK.

TYPE-WRITER ATTACHMENT.

1,294,351.

Specification of Letters Patent. Patented Feb. 11, 1919.

Application filed December 15, 1917. Serial No. 207,280.

To all whom it may concern:

Be it known that I, HARRY L. TANNER, a citizen of the United States of America, residing at 1144 East 19th street, Brooklyn, 5 in the county of Kings and State of New York, have invented certain new and useful Improvements in Type-Writer Attachments, of which the following is a specification.

10 This invention relates to means for attaching a typewriter or other office machine, such as an adding machine, to a desk or table drawer. The object of the invention is to provide means for supporting 15 said machines in an operable position when in use and for guiding the same into a reposing position within the drawer when not in use. My invention has especial adaptation to small size typewriters of the collapsible or folding type.

20 Referring to the drawings wherein I have shown what I now consider to be the preferred form of my invention:

Figure 1 is a perspective view of a typewriter attached to a drawer according to my invention and shown in the operative position.

Fig. 2 is a view of the typewriter folded or turned down into the drawer, so that the 30 drawer may be closed.

Figs. 3 and 4 are details showing different means for securing the machine to a bar which is in turn secured to the drawer.

Fig. 5 is a view of a modified form of bar. 35 In the drawings 1 represents a desk or table, one of the drawers 2 of which is shown open. A bar 3 preferably of metal is shown rotatably mounted in the drawer 2 near the top and front thereof. The bar is 40 preferably inclined at an angle to the front of the drawer so that when the typewriter is folded outwardly in the operative position the keyboard will be turned somewhat to the front so as to be in a readily accessible 45 position for the operator. The ends of the bar may fit rotatably into plates 4 which may be securely fastened to the sides 5 of the drawer as by screws 4'. The typewriter 7 having a keyboard 26 and carriage 20 may 50 be fastened to the bar by strips 6 fixed to said bar by being pressed therearound, or by any other suitable method and secured by screws or rivets 8 or the like, to the frame 9 of said typewriter.

55 My invention is especially adapted to the

small models of typewriters and particularly those in which the carriage is adapted to fold forwardly to effect a compact arrangement.

In the form shown, the carriage 20 folds 60 forwardly about pivots 21 and 22 connecting forwardly extending bars 23 and 24. When folded forwardly carriage 20 is rotated through approximately 180° and rests face downward on front piece 25.

65 In Fig. 1 the typewriter is shown in the operable position, attached as described to bar 3; and resting on its frame 9 on the front piece 10 of the drawing, the major portion reaching out beyond the edge of the drawer. When the machine is not in use, the carriage 20 may be folded forward as described in the well known manner and the machine turned over on bar 3 as a pivot, so as to assume an inverted position within the drawer as shown in Fig. 2, so that the 70 drawer may be closed.

75 As shown in Fig. 2, I may provide a foot 11 on the back piece 12 of the frame 9 of the machine to rest on the front edge 10 of the drawer if desired when the machine is in the operative position.

80 In Fig. 2, bar 3 is shown as comprising one piece, which may be cut to length upon ascertaining the width of the drawer to 85 which it is to be applied.

85 In Fig. 5 I have shown a modified form of bar 3' adapted to be adjusted to fit various widths of drawers. While any 90 form of extensible bar may be employed for this purpose, I have shown a bar comprising an outer or sleeve portion 3^a and an inner portion 3^b slidably inserted into said outer portion. Any suitable means, such as a set screw 13 may be used to lock the portions together in the desired position.

95 In Fig. 3 I have shown a modified type of clip for fastening the typewriter to the bar 3. This clip may comprise a portion 14 fixed on said bar and a portion 15 adapted to be fastened to portion 14 by means of a set screw 16, while the two portions may be bent over adjacent their ends 14' and 15' so as to embrace the two edges of frame 9 of the typewriter.

100 The preferred form of clip is shown in Fig. 4, and comprises a member 17 fixed on shaft 3 and adapted to be secured to projection 18 to which the rubber feet 19 of the typewriter are attached. For this pur- 110

pose the said feet may be removed and the clip fastened to said projection by means of a small bolt 20' passing through said clip and the hole 21' in which said feet are normally secured.

While I have illustrated my invention in connection with a small model of typewriter, it will readily be seen that it is equally adapted for use in connection with larger 10 models where the drawer is large enough to hold the machine, and that it may also be used for machines other than typewriters, such for instance, as adding or computing machines and the like.

15 Instead of having bar 3 rotate in end plates 4, and clips or clamping members 6 rigidly fixed on said bar, the bar may be rigidly fixed in said end plates and clamping members 6 may be made to rotate on 20 said bar. In this case, a stop collar 27 (Fig. 5) may be rigidly fixed to bar 3' on each side of clamping member 6 to prevent lateral movement of said members.

In accordance with the provisions of the 25 patent statutes, I have herein described the principle of operation of my invention, together with the apparatus, which I now consider to represent the best embodiment thereof, but I desire to have it understood that 30 the apparatus shown is only illustrative and that the invention can be carried out by other means. Also, while it is designed to use the various features and elements in the combination and relations described, some 35 of these may be altered and others omitted without interfering with the more general results outlined, and the invention extends to such use.

Having described my invention, what I 40 claim and desire to secure by Letters Patent is:

1. The combination with a desk having a drawer of ordinary size, of a typewriter having a folding carriage and a hinge for said 45 typewriter secured across the opening of said drawer whereby the typewriter may be folded in the inverted position within the drawer and turned back to an upright position above the drawer.

50 2. An attachment for a typewriter, comprising a bar of adjustable length, means for securing said bar to a typewriter, and means for mounting said bar in a drawer.

3. The combination with a desk having a 55 drawer, of a bar secured across the opening of said drawer at an angle to the front of the drawer and a typewriter attached to said bar.

4. In combination, a desk, a drawer, a bar 60 rotatably fixed across the inside and adjacent the top and front of said drawer, a

typewriter and means for attaching said typewriter to said bar.

5. Means for attaching a typewriter to a drawer, comprising a bar, end plates for 65 said bar adapted to be attached to said drawer, projections on said bar and means for attaching a typewriter to said projections.

6. The combination with a desk having a 70 drawer of the average depth, an office machine hinged within said drawer so as to fold thereto and means for supporting said machine in an operative position on the end of said drawer when said machine 75 is lifted out of said drawer.

7. Means for attaching a typewriter to a drawer, comprising an extensible bar, end plates for 80 rotatably supporting said bar and adapted to be attached to said drawer and means for attaching said typewriter to said bar.

8. Means for attaching a typewriter to a drawer comprising a bar, end plates for 85 rotatably supporting said bar, means for securing said end plates to said drawer and projections on said bar, adapted to be attached to the feet supporting member of a typewriter.

9. Means for attaching a typewriter to a 90 drawer, comprising a bar, end plates for rotatably supporting said bar, means for securing said end plates to said drawer and a clamping member on said bar.

10. The combination with a desk having 95 a drawer, an office machine, means for supporting said typewriter on the edge of said drawer with the major portion thereof projecting outwardly from said edge, and a hinge for said machine adjacent said edge 100 and the top of the drawer whereby said machine may assume an inverted position within said drawer.

11. The combination with a drawer and a desk, of an office machine having a keyboard, pivoted therein adjacent the outer edge of the drawer whereby said machine may be folded upside down within the drawer and may be supported by the front of the drawer with the keyboard in the 110 operative position.

12. The combination with a desk having an average size drawer, a typewriter hinged to and adapted to fold into said drawer when not in use and above and beyond the 115 drawer when operative, the front of the drawer serving to support the same in the last named position.

In testimony whereof I have affixed my signature.

HARRY L. TANNER.
